By

UNITED STATES PATENT OFFICE.

CHARLES SCHEDELL, OF PHILADELPHIA, PENNSYLVANIA.

DESIGN FOR STICKY FLY-PLATE.

No. 39,263.

Specification for Design.

Patented April 14, 1908.

Application filed February 17, 1908. Serial No. 416,432. Term of patent 7 years.

To all whom it may concern:

Be it known that I, CHARLES SCHEDELL, a citizen of the United States, residing at Philadelphia, in the county of Philadelphia and State of Pennsylvania, have invented a new, original, and ornamental Design for Sticky Fly-Plate, of which the following is a specification, reference being had to the accompanying drawing, forming part thereof.

The figure is a plan view of a sticky fly plate, showing my new design.

I claim.

The ornamental design for a sticky fly plate, as shown.

CHARLES SCHEDELL.
